(57) **CLAIM**

The ornamental design for a lawn apparatus, as shown and described.

DESCRIPTION

FIG. 1 is a perspective view of a lawn apparatus showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines shown in the drawings illustrate portions of the lawn apparatus that form no part of the claimed design.
